UNITED STATES PATENT OFFICE.

JOHN L. BOGERT, OF WALTHAM, MASSACHUSETTS, ASSIGNOR TO WALTHAM WATCH COMPANY, OF WALTHAM, MASSACHUSETTS, A CORPORATION OF MASSACHUSETTS.

DESIGN FOR A WALL-CLOCK CASING AND DIAL.

51,833.

Specification for Design.

Patented Mar. 5, 1918.

Application filed August 16, 1917. Serial No. 186,637. Term of patent 14 years.

To all whom it may concern:

Be it known that I, JOHN L. BOGERT, a citizen of the United States, residing at Waltham, in the county of Middlesex and State of Massachusetts, have invented a new, original, and ornamental Design for a Wall-Clock Casing and Dial, of which the following is a specification, reference being had to the drawing, forming a part thereof.

The figure is a front elevation of a wall clock casing and dial showing my design.

The design comprises a frame adapted to be placed against or hung upon a wall, said frame being divided into two panels, of which the upper panel displays a clock face, and the lower panel contains a mirror.

I claim:

The ornamental design for a wall clock casing and dial as shown and described.

JOHN L. BOGERT.
